(57) CLAIM

The ornamental design for a “corner wine bar,” as shown and described.

DESCRIPTION

FIG. 1 is a front perspective view of a corner wine bar showing my new design;

FIG. 2 is a front elevational view of the corner wine bar of FIG. 1;

FIG. 3 is a rear elevational view of the corner wine bar of FIG. 1;

FIG. 4 is a left elevational view of the corner wine bar of FIG. 1;

FIG. 5 is a right elevational view of the corner wine bar of FIG. 1;
